US00D961522S

(12) **United States Design Patent** (10) **Patent No.:** **US D961,522 S**
Li (45) **Date of Patent:** **** Aug. 23, 2022**

(54) **POWER STRIP**

(71) Applicant: **Huimin Li**, Guangdong (CN)

(72) Inventor: **Huimin Li**, Guangdong (CN)

(**) Term: **15 Years**

(21) Appl. No.: **29/769,174**

(22) Filed: **Feb. 3, 2021**

(51) LOC (13) Cl. **13-03**

(52) U.S. Cl.

USPC **D13/139.8**

(58) **Field of Classification Search**

USPC ... D13/123, 133, 137.1, 137.2, 137.3, 137.4, D13/138.1, 138.2, 139.1, 139.2, 139.3, D13/139.4, 139.5, 139.6, 139.7, 139.8, D13/151, 152, 153, 154, 155, 156, 157, D13/158, 159, 184, 199, 103, 107, 108

CLAIM

The ornamental design for a power strip, as shown and described.

DESCRIPTION

FIG. 1 is a perspective view of a power strip showing my/our new design;

FIG. 2 is a front view thereof;

FIG. 3 is a back view thereof;

FIG. 4 is a left side view thereof;

FIG. 5 is a right side view thereof;

FIG. 6 is a top view thereof; and,

FIG. 7 is a bottom view thereof.

The broken lines in the drawing depict environmental subject matter only and form no part of the claimed design.

1 Claim, 7 Drawing Sheets
